TAPE-APPLYING MACHINE

Harry D. Elliott, Wenham, Mass., assignor to
United Shoe Machinery Corporation, Flemington, N. J., a corporation of New Jersey

Application July 30, 1942, Serial No. 452,927

17 Claims. (Cl. 12—51)

This invention pertains to machines for applying a reinforcing tape to articles and more especially to applying a precoated reinforcing tape to vamp throats.

In blucher and bal type shoes it is desirable to reinforce the vamp throat with tape along that portion to which the quarters of the shoe are attached in order to strengthen the connection and to prevent the attaching means from pulling out under the strain of the lasting operations or of subsequent wear. The reinforcing tape in both types of vamp lies along the base of the throat and in the bal type is comparatively short since the quarters are attached to the vamp at the center of the throat. The blucher type vamp throat stay, however, is longer since the quarters are attached at the opposite sides of the throat.

It has been customary in many factories to apply the reinforcing tape to the underside of the vamp by hand and while machines have been designed for applying tape to the vamp throat they have not met with general success because they have been complicated, expensive to build and not fast enough to compete with hand work.

It is an object of the present invention, therefore, to provide an improved tape-applying machine in which the tape-advancing, cutting and applying means are combined in a simple mechanism, inexpensive to build, rapid and efficient in operation, and affording ready and convenient positioning of the work.

In general, the preferred machine comprises tape-severing and applying means operable to sever a predetermined length of tape, from a continuous length of tape advanced by oscillatory feeding means having a releasable tape-engaging member, and applying it to the underside of the vamp throat. As illustrated, invention resides in means for holding the free end of the tape remainder during the return movement of the tape-feeding means for a succeeding length of the tape, means for releasing the tape-engaging member and holding it ineffective during the greater part of return movement of the tape-feeding means, and means for opening the holding means and rendering the releasable means effective prior to the termination of the return movement.

The invention will now be described in detail with reference to the accompanying drawings, in which

Fig. 1 is a side elevation of the machine, partly in section, taken on the line I—I of Fig. 6;

Fig. 2 is a fragmentary side elevation of the

pressure-applying means, showing a part of the tape-severing means and the adjustment therefor;

Fig. 3 is a vertical transverse section taken on the line III—III of Fig. 6;

Fig. 4 is a fragmentary similar section, but showing the work gripped by the pressure-applying means;

Fig. 5 is a fragmentary plan view of the pressure-applying means with the work-backing means removed;

Fig. 6 is a plan view of the entire machine, broken away in part to show the operating mechanism for the tape-feeding and pressure-applying means;

Fig. 7 is a fragmentary perspective view of the backing means;

Fig. 8 is a perspective view of the pressure-applying means;

Fig. 9 is a detail vertical section on the line IX—IX of Fig. 6;

Fig. 10 is a plan view of the backing means overlying the work;

Figs. 11 and 12 show bal and blucher vamps with tape applied thereto; and

Fig. 13 is a detail of the tape support taken on the line XIII—XIII of Fig. 3.

The machine of the present invention is for applying a reinforcing tape, one side of which is coated with adhesive preferably of the pressure sensitive type, to parts of shoes and particularly to the throat of either the blucher or bal type vamp at the portion to which the adjacent corners of the quarters are stitched, thereby to reinforce that portion to prevent the parts from pulling away from each other under the strain of lasting or subsequent wear. A bal type vamp V is shown in Fig. 11 and in that type of vamp a short piece of tape t is applied to the flesh or non-display side of the vamp at approximately the center of the vamp throat where the quarters come together and are attached to the vamp. In the blucher type of vamp V' (Fig. 12) the quarters are stitched thereto at the opposite sides of the throat and, accordingly, the tape t is laid across the entire throat. It is to be observed that the machine is not limited in its use to the application of reinforcing tape to vamps, but that it may also be employed for applying tape to other parts of shoes, for example, back seams, eyelet rows, etc.

Referring to Figs. 1 and 3, the machine comprises, generally, a support 10 for the work to which the tape is to be applied and upon which the work is disposed with its flesh surface down,

tape-feeding means 12 for moving a predetermined length of tape in a plane beneath the work support to a position in which it may be applied to the work, means 14 for severing the advanced length of tape from its source of supply, and means 16 for pressing the severed tape into engagement with the work, an opening 18 being provided in the work support through which the pressure-applying means raises the tape into engagement with the flesh side of the work. The aforesaid means are housed in a hollow base 20 which is of a generally rectangular shape, the removable top portion thereof at the front of the machine being stepped down and having a slightly inclined, transversely extending cover which constitutes the support 10 for the work. The inclination of the cover is toward the operator and permits a substantially plan view of the work. The opening 18 provided in the cover of the support 10 is partially closed by a plate 22 (Fig. 6) set into the opening 18 and removably secured to the inclined cover by a tongue-and-groove construction, this plate having at its inner end an opening 24 over which the work is placed and through which a predetermined length of tape is raised into contact with the work. By sliding the plate 22 from the support 10 access may be had to some of the parts below the support without removing the entire top portion of the machine.

The tape reel for supplying tape to the machine is supported on a bracket 26 bolted to the side of the machine (Figs. 3 and 13), the bracket having fixed to its free end a spindle 28 upon which are mounted a pair of spaced disks 30 between which the reel of tape is disposed on the spindle. One of the disks 30 abuts the bracket 26 at the inner end of the spindle and the other is yieldably urged toward it by a strip of spring steel 32 riveted to the disk and having an aperture therein so that it may be slipped over the end of the spindle with the disk. The free ends of the strip 32, which are provided with enlarged apertures 33, are bent outwardly away from the disk and back upon themselves so that they may be brought into engagement with the spindle and locked in a predetermined position by engagement with grooves 36 formed thereon. By changing the position of the ends of the spring in the grooves formed in the spindle, the movable disk 30 may be caused frictionally to engage the side of the reel of tape to provide more or less resistance to turning, as desired. A disk 31 placed on the spindle 28 engages the inside of the core of the tape reel, thereby holding it concentric with the spindle.

The tape is unwound from the tape reel by the tape-feeding means 12. Since one coil of tape tends to adhere to the succeeding coil, there is a tendency, when the tape is unwound, for the feeding means to pull the tape unevenly away from the reel, and, in order to prevent this, a drag or braking roll 34 is provided between the tape reel and the feeding means which engages the tacky surface of the tape and prevents sudden delivery of an excess amount of tape by irregularities in the rotation of the tape reel. The drag roll 34 is mounted on a horizontally disposed stud 36, the latter being fastened at one end to the bracket 26 by a setscrew 38. The tape is held by a vertical abutment 39 with its rear edge in alignment with work-positioning gages, to be hereinafter de-

scribed. A finger 40 is provided for engaging the front edge of the tape thereby to hold the rear edge against the abutment 39, the finger being adjustable for different widths of tape. 5 To this end, as illustrated, the finger 40 is attached to the bracket 26 adjacent to the drag roll 34 by a screw-and-slot connection 42 and is adjustable transversely of the tape (Figs. 3 and 6).

10 The tape-feeding means 12 comprises, as is shown in Figs. 3 and 4, a horizontal plate 44 against the underside of which the tape is held by an arm 46 having a blunt edge which bites into the tape when it is forced toward the plate 44. The plate 44 is reciprocated in a horizontal plane to move the tape into a position beneath the opening 24 and is mounted for reciprocation with a flat bar 48 which is slidable in a slot 50 formed on the underside of the support 10. To 15 this end, a vertical web 52 (Fig. 2) is formed integral with the horizontal plate 44 and from the web 52 there extends a rib 54 which is fastened by screws 53 in a transverse groove 56 formed in the upper surface of the bar 48. The 20 arm 46, which co-operates with the plate 44 to grip the tape, is pivotally mounted on a stud 60 (Fig. 5) extending from the web 52, the arm normally being urged in a direction to bite into the tape by a spring 62 fastened at one end to the arm and at the opposite end to the web 52. The reciprocation of the sliding bar 48, and consequently of the tape-feeding means, is produced by a lever 64 (Fig. 6) one end of which is pivotally attached by a pin 65 to the underside of the sliding bar 48. The lever 64 is supported between its ends upon a vertically disposed spindle 66 (Figs. 6 and 9) for oscillation in a horizontal plane, the oscillation about the spindle being produced by a cam follower 68 25 which is fastened to the opposite end of the arm. The cam follower occupies a cam slot 70 formed in a cam 72. The cam 72 is fastened by a pin 74 to a drive shaft 76, the latter being driven by a pulley 78 which is loosely mounted on the shaft and may be connected thereto to produce a single revolution of the shaft by a one-revolution clutch 80 which is treadle operated, the treadle rod being shown at 82.

The length of the tape to be applied to the work will vary with the type of vamp, that is, whether it is a blucher or bal, as explained above, and accordingly the tape-feeding means is constructed so that the length of tape may be varied to suit the kind of work being operated upon. This is accomplished herein by changing the position of the spindle 66 about which the lever 64 oscillates to increase or decrease the throw of the end of the arm which is connected to the sliding bar 48. As illustrated, a slot 84 is formed in the lever 64 and a block 86 is slidably disposed in the slot about the spindle 66. The ends of the spindle 66 pass through the walls 88 of a bifurcated block 90, the slotted portion of the lever 64 being confined by the spindle 66 and block 86 between the walls 88. The block 90 is slidably supported between ways 92 formed on the inside wall of the base 20 and is held in a selected position by a stem 94 which passes through a slot 96 formed in the wall and a thumb nut 98 threaded over the projecting end of the stem and abutting a plate 100 disposed between the outer surface of the wall and the thumb nut. 50 By backing off the thumb nut 98, the block 90 may be moved along the ways 92 thereby to shift the position of the spindle 66 and block 86 in

the slot 84 of the lever 64. By shifting the spindle 66 toward the front of the machine, the throw of the end of the lever 64 is shortened and by shifting the spindle 66 toward the back of the machine, the throw of the lever 64 is increased. The plate 100 is provided with an index or pointer 102 which registers with a scale (not shown) graduated in quarter inches on the side wall of the machine so that the operator may, by adjusting the position of the index along the scale, increase or decrease the length of the tape known amounts.

Prior to the application of the tape to the work by the pressure-applying means 16, the tape must be severed from the remainder of the tape. In order to provide a clean cut during the severing operation it is desirable to hold the projecting end of the tape close to the point at which it is to be cut and, accordingly, tape-clamping means 104 (Figs. 3 and 4) is provided a portion of which is mounted, together with a part of the tape severing means, upon the pressure-applying means and is movable therewith at right angles to the plane of the tape toward the work support. The tape-clamping means 104 comprises a fixed bar 106 and a movable plate 108, the edges of the bar and plate being co-operative by movement of the plate into engagement with the bar to grip the tape. The bar 106 is fastened to the support 10 along one edge of the opening 24 and is provided with a vertical downwardly extending surface and an upwardly inclined surface extending backwardly from the vertical surface. The plate 108 is slidably mounted on one side of the pressure-applying member 16, as seen in Figs. 3 and 4, being retained in position by the base 110 of a bracket 112, the purpose of which will be described hereinafter, which is fastened by screws 114 to the pressure-applying member. The plate 108 occupies a vertical position and its upper edge is cut backwardly and downwardly so that the apex formed by the sloping surface and the vertical inner surface of the plate co-operate with the edge of the bar 106 to bite the tape. A bore is formed in the bottom edge of the plate 108 for the reception of a compression spring 116 the lower end of which is backed up by a plate 118 fastened by screws 120 to the bottom of the pressure-applying member 16. Thus, the pressure-applying means 16 may continue to move upwardly after the tape-clamping means have been brought together to grip the tape, the lower member 108 of the clamping means remaining stationary while the pressure-applying means moves by it, compressing the spring 116, as shown in Fig. 4. A pin 122 fastened to the pressure-applying means 16 is provided, for withdrawing the plate 108 as the pressure-applying means descends, the end of the pin engaging a ledge 124 formed on the inner side of the plate 108.

The severing means 14 comprises both the bar 106 which forms the fixed portion of the tape-clamping means and a hardened steel plate 126 which is fastened to the top of the pressure-applying means, the upper surface of the plate providing the means for contacting the tape and pressing it into engagement with the work as the pressure-applying means 16 rises. The hardened steel plate 126, as shown in Figs. 2 and 8, is provided with a depending flange 128 having a slot 130 therein through which there is passed a bolt 132 for securing the plate in position. The inner edge of the plate, as shown in Figs. 3 and 4, lies in the plane of the vertical surface of the bar 106 and when moved upwardly co-operates with

the lower edge of the bar 106 progressively to shear the tape transversely. The plate may be adjusted on the pressure-applying means to bring its edge into a proper shearing relation with the bar 106 and for this purpose a screw 134 (Fig. 8) is threaded into the side of the pressure-applying means 16 so that its head engages the edge of the steel plate 126 opposite the shearing edge. By releasing the bolt 132 and rotating the screw 134, the position of the plate 126 may be adjusted inwardly or outwardly as is desired. During the shearing operation there is a tendency for the pressure-applying means to be thrust to one side, especially if the shearing instrumentalities have become dull or the tape is especially heavy. If this occurs, the cut is ragged and sometimes the displacement is of such magnitude that the tape is not sheared but is merely bent upwardly between the shearing surfaces. To prevent such displacement, a roll 136 (Fig. 3) is positioned for engagement with the side face of the pressure-applying means opposite the shearing edge. The roll 136 is mounted on a spindle 138 journaled in the walls of a slot 140 formed in the upper end of a bracket 142, the latter being bolted to the base at 144.

The pressure-applying means 16, tape-clamping plate 108, and severing plate 126 are reciprocated in a direction at right angles to the tape by an arm 146 (Figs. 1, 6 and 8), the pressure-applying means 16 comprising a block formed integrally with one end thereof. The arm 146 is mounted between its ends upon a horizontal spindle 148, the latter being journaled at its ends between a pair of uprights 150 rising from the bottom of the housing. The opposite end of the arm 146 is provided with a yoke-shaped portion 152 (Fig. 1) which is arranged to encompass a cam 154 fastened by a pin 156 to the shaft 76. Rotation of the cam 154 oscillates the arm 146 and produces vertical reciprocation of the pressure-applying means.

When the tape has been fed into a position beneath the opening 24 in the work support 10 and a predetermined portion severed therefrom and moved upwardly by the pressure-applying means into engagement with the work, the superposed pieces are pressed, by further upward movement of the pressure-applying means, against a backing means 158 which is arranged to receive the upward thrust of the pressure-applying means so that the tape will be firmly united with the work. The backing means 158, as shown in Figs. 1 and 7, comprises a block 160 of transparent material, such as nonshatterable glass or a plastic, which overlies and is spaced from the surface of the work support in a position to contact the display surface of the work when the pressure-applying means thrusts the tape against the work. Since the block 160 is transparent, the operator may observe the position of the work beneath it and may adjust the work with respect to a hairline 162 formed on the surface of the block to a position in which the center of that portion of the work which is to be reinforced lies midway between the ends of the tape which is below the work support and which the operator cannot see. The block 160, as will appear hereinafter, is adjustable to bring the hairline to a position in which it lies midway between the ends of the severed tape. The transparent block 160 is mounted on a forked block 164 and is held in notches 166 formed in the lower edges of a pair of parallel spaced arms 168 thereon, the block being pivotally mounted upon the ends of a spindle

168 (Fig. 1), the spindle in turn being supported by a bracket 170 which is attached by bolt-and-slot connections 171, 172 (Fig. 6) to the work-supporting cover 10 of the machine. A shouldered bolt 174 which is threaded through the bracket 170 is passed through the forked block 165, the shouldered portion engaging the top side of the block and providing means for adjusting the arms 166 about the spindle 168. This adjustment permits the operator to raise or lower the transparent block 160 with respect to the work support for different thicknesses of work. A set-screw 176 is provided for locking the bolt 174 in an adjusted position. To prevent damage to the transparent block 160, the arms 166 are yieldably maintained in their adjusted position by a compression spring 177 mounted on the bolt 174, the lower end of the spring abutting a washer 178 and the upper end being seated in a recess 180 formed in the block 165. The resistance to yielding may be varied by shortening or lengthening the spring 177, a nut 182 being provided for this purpose. The transparent block 160 is removable and the means for clamping it in the notches 164 comprises a screw 184 (Fig. 7) which passes between the arms 166 and may be manipulated to draw the arms toward each other thereby to grip the edges of the block 160. It is to be observed that in order to maintain the hairline 162 on the transparent block midway between the ends of the tape for different lengths of tape, means must be provided for adjusting the position of the block longitudinally of the tape. This is made possible by movement of the bracket 170 on the support longitudinally of the tape, the bolt-and-slot connections 171, 172 previously referred to providing for ready adjustment of the bracket.

In order to locate the fore and aft position of the work on the support 10, gages are provided for engagement with the throat of the vamp. In order to provide for either the bal or blucher type shoe, two gages 186, 188 (Fig. 1) are mounted above the work support 10 upon the bracket 170 in such a manner that one or the other may be employed as is desired. When applying tape to the bal type vamp V (Fig. 11), a single gage point is sufficient and for this purpose the gage 188 is employed, this gage having a bent end 190 which engages the top of the support and, as shown in Fig. 10, has a surface parallel to the edge of the tape. By holding the vamp throat against this gage, the work may be positioned so that the edge of the tape and the throat are aligned. In the blucher type vamp V' (Fig. 12), the vamp throat has an inwardly projecting tongue and consequently other gaging means must be provided. Accordingly, the gage 186, which is shown in Fig. 1, is mounted on top of the gage 188 and is slidable from a retracted position downwardly into contact with the work, the end 192 of this gage being bifurcated so that it straddles the tongue. A thumbscrew 194 passed through slots in both of these gages fastens them to the bracket 170 and provides means for locking one or the other in an operative position.

During the tape-severing operation, as heretofore described, the tape is held by the clamping means 106-108. Due to the fact that one surface of the tape is tacky, when the clamping means separate upon the reverse movement of the pressure-applying means, the end of the tape would adhere to the upper fixed portion 196 of the clamping means. As a result, when the succeeding feeding motion is imparted to the tape-

feeding means, the end of the tape which is stuck to the clamping means would not advance and a loop would be formed in the tape which would fold upon itself and, consequently, would not properly be applied to the work. To eliminate this, the feeding means 12 is so constructed that near the end of its reverse movement it will retract the tape sufficiently to pull it away from the clamping means 106. This is accomplished by the relative timing of the tape-gripping and the tape-feeding means. As shown in Fig. 4, when the pressure-applying means 16 is in pressure-applying position, the upper surface 196 of the bracket 112 engages the lower end of the arm 46 and tilts it about its pivot 60 so that the tape-engaging portion thereof is held away from the plate 44. Accordingly, as the tape-feeding means 12 is retracted by the lever 64, it moves backwardly along the tape without gripping it. Near the end of the return stroke, however, the pressure-applying means 16 has begun to move in its reverse direction and the surface 196 moves away from the lower end of the arm 46 so that the tape-engaging portion of the latter again grips the tape, thereby giving it a short reverse pull before the lever 64 completes its oscillation.

When the machine is in operation, the stroke of the tape-feeding means is first adjusted by positioning the index or pointer 102 opposite the proper indicia on the scale and then the work is placed with its flesh surface down upon the work support 10 over the opening 24 and below the transparent block 160 with its throat edge in contact with the appropriate gage. The hairline 162 on the transparent block 160 is then used as a guide for positioning the work lengthwise of the tape so that the point to which the tape is to be applied lies substantially equally on opposite sides of the hairline 162, the operator being able to make this adjustment accurately beneath the transparent plate which permits an unobstructed view of the work. Having positioned the work transversely and also fore and aft by means of one or the other of the gages 186, 188, the operator trips the one-revolution clutch 80, whereupon the feeding means 12 moves the tape to a position beneath the opening 24. Simultaneously, the pressure-applying means begins to ascend, the tape clamps 106, 108 come into engagement with the opposite sides of the tape and hold it during the severing operation which follows immediately. After the tape is severed, the continued upward movement of the pressure-applying means lifts the severed tape into engagement with the work and presses the superposed pieces against the transparent block 160. During the latter part of the forward movement of the pressure-applying means the surface 196 comes into contact with the lower end of the arm 46, thereby releasing the tape so that during the reverse movement of the feeding means the tape is not gripped. Near the end of the reverse movement of the tape-feeding means, however, the pressure-applying means begins to descend and during the last part of the movement of the tape-feeding means moves the surface 196 away from the arm 46 sufficiently to permit the tape-engaging portion thereof to again grip the tape, thereby pulling the tape back a small amount and disengaging it from the tape-clamping means. The cycle of operation is then complete and the work is removed from the machine.

Having described my invention, what I claim as new and desire to secure by Letters Patent of the United States is:

1. In a tape-applying machine having tape-severing and applying mechanisms, an oscillatory tape-feeding device having a releasable tape-engaging member, means for holding the free end of the succeeding tape during the return movement of the feeding device, means for releasing the tape-engaging member, and means for releasing said holding means prior to the termination of said return movement, said last-named means being constructed and arranged to cause a recession of the tape to separate said free end from the holding means.

2. In a tape-applying machine, oscillatory tape-feeding mechanism having a releasable gripper, a movable member arranged to hold the free end of the tape during the return movement of the feeding mechanism, said member being constructed and arranged to release said gripper, and means for opening the holding means and rendering the gripper effective prior to the termination of the return movement.

3. In a machine for applying tape to a shoe part, an apertured support arranged to receive the shoe part with the portion to which the tape is to be applied overlying the aperture, tape-feeding means operable to advance a predetermined length of tape below the aperture in the support, means for severing the tape, and means for lifting the severed tape into engagement with the shoe part, said last-named means being constructed and arranged to cause the severing means to sever the tape and thereafter to discontinue the effectiveness of the tape-feeding means.

4. In a machine for applying tape to a shoe part, an apertured support arranged to receive the shoe part with the portion to which the tape is to be applied overlying the aperture, tape-feeding means operable to advance a predetermined length of tape below the aperture in the support, means for severing the tape, means for holding the tape adjacent to the point at which it is severed, and pressure-applying means operable to lift the severed tape into engagement with the shoe part, said tape-severing means being constructed and arranged to cause the holding means to grip the tape and thereafter to discontinue the effectiveness of the tape-feeding means.

5. In a machine for applying tape to a shoe part, an apertured support arranged to receive the shoe part with the portion to which the tape is to be applied overlying the aperture, oscillatory tape-feeding means, means for oscillating the tape-feeding means to advance a length of tape beneath the aperture and for then returning the tape-feeding means for a succeeding length of tape, means for severing the advanced tape, and means for lifting the severed tape into engagement with the shoe part, said last-named means being constructed and arranged to cause the feeding means to release the tape at the end of its advancing movement and to re-engage the tape near the end of its return movement.

6. In a machine for applying tape to a shoe part, an apertured support arranged to receive the shoe part with the portion to which the tape is to be applied overlying the aperture, oscillatory tape-feeding means, means for oscillating the tape-feeding means to advance a length of tape beneath the aperture, means for severing the tape, means for holding the tape adjacent to the point at which it is severed, and pressure-applying means operable to lift the severed tape into engagement with the shoe part, said severing and holding means comprising, in common, a fixed

bar having angularly related surfaces and members mounted on the pressure-applying means and movable therewith, one of said members having a surface extending in advance of the pressure-applying means and the other having a surface in the plane of the pressure-applying means, the movement of the pressure-applying means being operable to bring the surface of the one member into engagement with one of the surfaces of the fixed bar and thereafter to move the surface of the other member past the other surface of the fixed bar in shearing relation to said last-named surface.

7. In a machine for applying tape to a shoe part, an oscillatory tape-feeding means having a releasable gripper, means for causing the tape-feeding means to advance a predetermined length of tape and to return for a succeeding length of tape, and means for severing the tape, said last-named means being constructed and arranged to release the gripper prior to the beginning of the return movement of the tape-feeding means.

8. In a machine for applying tape to a shoe part, an oscillatory tape-feeding means comprising jaws to engage the tape, said tape-feeding means being operable to advance a predetermined length of tape, tape-severing means operable to sever said predetermined length of tape, and an arm associated with the tape-severing means operable to separate the jaws at the end of the advance feeding movement.

9. In a machine for applying tape to a shoe part, an oscillatory tape-feeding means comprising jaws to engage the tape, means for oscillating the tape-feeding means to advance a length of tape and to return the jaws for a succeeding length of tape, tape-severing means, means for holding the free end of the succeeding tape during the return movement of the feeding means, and an arm associated with said tape-severing means and movable therewith to separate the jaws at the end of the advancing movement of the jaws, the timing of the parts being such that said arm holds the jaws separated during the major portion of the return movement of the jaws.

10. In a machine for applying tape to a shoe part, an oscillatory tape-feeding means comprising a fixed and a movable jaw, means for oscillating the tape-feeding means to advance a predetermined length of tape and to return for a succeeding length of tape, tape-severing means, movable means to cause said tape-severing means to sever the tape, and an arm associated with the last-named means and movable therewith to engage the movable jaw and separate it from the fixed jaw at the end of the advancing movement of the tape-feeding means, said arm being retracted by the reverse movement of said last-named means to permit re-engagement of the movable jaw with the tape near the end of the return movement of the tape-feeding means.

11. In a machine for applying tape to a shoe part, an oscillatory tape-feeding means comprising a fixed jaw and a movable jaw spring pressed toward the fixed jaw, means for oscillating the tape-feeding means to advance a predetermined length of tape and to return the tape-feeding means for a succeeding length of tape, means for severing the tape, means for actuating said severing means, and means carried by said actuating means to maintain the movable jaw separated

from the fixed jaw during the greater part of the return movement of the tape-feeding means.

12. In a machine for applying tape to a shoe part, an apertured support arranged to receive the shoe part with the portion to which the tape is to be applied overlying the aperture, tape-feeding means, means for oscillating the tape-feeding means to advance a length of tape beneath the aperture, means for severing the tape, pressure-applying means, a pressure plate mounted above the aperture in the support, and means for moving the pressure-applying means through said aperture to lift the severed tape into engagement with the shoe part and thereafter to press the superposed pieces against the pressure plate, said pressure plate being adjustable on the support lengthwise of the tape. 10

13. In a machine for applying tape to a shoe part, an apertured support arranged to receive the shoe part with the portion to which the tape is to be applied overlying the aperture, oscillatory tape-feeding means, means for oscillating the tape-feeding means to advance a length of tape beneath the aperture, means for severing the tape, pressure-applying means operable to lift the tape into engagement with the shoe part, a pressure plate mounted above the aperture in the support, means for moving the pressure-applying means through said aperture to lift the tape into engagement with the shoe part and thereafter to press the superposed pieces against the pressure plate, and gage means mounted on said pressure plate to locate the shoe part on the support. 20

14. In a machine for applying tape to a shoe part, an apertured support arranged to receive the shoe part with the portion to which the tape is to be applied overlying the aperture, oscillatory tape-feeding means, means for oscillating the tape-feeding means to advance a length of tape beneath the aperture, means for severing the tape, pressure-applying means, a pressure plate mounted above the aperture in the support, means for moving the pressure-applying means through said aperture to lift the severed tape into engagement with the shoe part and thereafter to press the superposed pieces against the pressure plate, plural gages mounted on said pressure

plate for different kinds of work arranged to engage an edge of the work on the support, and means for holding one of said gages in gaging position while holding the other of said gages in an out-of-the-way position. 5

15. In a machine for applying tape to a shoe part, an apertured support arranged to receive the shoe part with the portion to which the tape is to be applied overlying the aperture, a pressure plate, means for lifting a piece of tape through the aperture into engagement with the shoe part and thereafter pressing the superposed pieces against the pressure plate, and means for supporting said plate on said support above said aperture, said means comprising a bracket adjustably fixed to said support, a spindle carried by said bracket, means pivotally mounted on said spindle to hold the pressure plate, and means for yieldably holding said last-named means in a predetermined position on said spindle. 15

16. In a machine for applying tape to a shoe part, an apertured support arranged to receive the shoe part with the portion to which the tape is to be applied overlying the aperture, tape-feeding means arranged to move a length of tape below the aperture, a lever supporting the tape-feeding means for oscillation, a fulcrum supporting the lever, a cam co-operating with the lever and causing oscillation thereof about the fulcrum, and means for adjusting the position of the fulcrum to vary the length of oscillation of the tape-feeding means. 25

17. In a machine for applying tape to a shoe part, an apertured support arranged to receive the shoe part with the portion to which the tape is to be applied overlying the aperture, tape-feeding means arranged to move a length of tape below the aperture, tape-severing means operable to cut a predetermined length of tape, pressure-applying means for lifting the severed tape into engagement with the shoe part, a lever supporting the tape-feeding means, a lever carrying the tape-severing and pressure-applying means, a common drive shaft, and cams on said drive shaft operable to oscillate the respective levers in horizontal and vertical planes. 30
